UNITED STATES PATENT OFFICE.

OSKAR SIMENSEN AND AXEL COLBAN, OF CHRISTIANIA, NORWAY.

TEMPORARY BINDER.

Application filed October 22, 1920. Serial No. 418,770.

To all whom it may concern:

Be it known that we, OSKAR SIMENSEN, bookbinder, and AXEL COLBAN, bookbinder, citizens of Norway, both residing at Kirkegaten 34, Christiania, Norway, have invented 5 certain new and useful Improvements in or Relating to Temporary Binders (for which we have filed an application in Norway March 31, 1919, No. 16,185), of which 10 the following is a specification.

Various systems of portfolios or binders for registering or filing documents are already known. In the case of the systems now best known the documents or periodicals which are to be placed in the binder are first perforated and then fastened in the binder through the perforations. According to another system the documents are placed between two clips, which have to be 20 opened every time it is desired to insert a fresh document. The first system undoubtedly ensures a good arrangement and orderly filing of the documents but their perforation with two or it may be more holes, is 25 prejudicial. The second system possesses the drawback that the documents have a tendency to fall out and become disarranged when fresh documents are inserted, more particularly if numerous documents are already contained in the portfolio. 30

Now the object of the present invention is to do away with these drawbacks, and it is characterized more especially by the fact that clip-bars made of flexible material are inserted in holders mounted in 35 each end of the binder. The ends of the clip-bars are provided with grooves or notches the object of which is to hold the clip-bars fast by engaging both ends of 40 suitably shaped flanges provided in the holders.

In the accompanying drawings a constructional form of the invention is shown by way of example.

45 Fig. 1 is an end view of the binder.

Fig. 2 is a plan view of the inside of the binder.

Fig. 3 is a sectional view on the line 1—1 of Fig. 2.

50 Fig. 4 illustrates a single clip-bar.

In the drawings 1 designates the back of the binder and 2 are the covers which are attached to the latter by means of flexible connecting parts 3. On the inside of the 55 back of the binder and at each end thereof are secured by means of rivets or the like

holders 4 the outer ends of which are bent upwardly and inwardly to form flanges 5, facing each other. The sides of the holders are also bent upwards to form projecting flanges 6.

In the drawings the flanges 5 are shown parallel, but it may be more advantageous to arrange the flanges so that they converge towards the side upon which the documents are inserted, thus ensuring a more secure clamping of clip-bars 7 hereinafter described.

The clip-bars 7, or it may be clip-rods, consist of thin flexible strips of metal or other suitable material. The ends of the clip-bars are provided with grooves or recesses 8, which engage with the flanges 5 whereby they are held in position. The side flanges 6 serve to restrict the movement of the clip-bars or rods in a lateral direction.

The outermost clip bar 9 is by preference thicker or stronger than the others and is provided at each end with suitably formed springs 10, which bear against the flange 6 on the one side of the holders at each end of the binder; the springs serving to press the clip-bars against the opposite sides of the holders, so that the whole arrangement becomes rigid and immovable. The documents or papers to be bound are turned over along their inner edges and then the clip bars are inserted in the folded portion. The clip-bars are now engaged between the flanges 5 of the holders by bending or deflecting the clip bars sufficiently to permit the flanges 5 to enter the grooves 8, or otherwise, and when all the clip-bars are properly placed in position the rod 9 with the spring 10 is inserted on the one side to prevent the clip-bars from becoming disengaged. With this arrangement it is possible to take out any individual document required and reinsert it at any point that may be desired on the binder. 90

Having thus fully described our invention what we claim as new and desire to secure by Letters Patent is:—

1. In a temporary binder and in combination with the covers and a back therefor, a binder comprising plates secured adjacent the ends on the back and each having a channel extending across the back and side flanges extending at right angles to the back, a plurality of binder members each adapted to removably engage with and 105 110

move on the outer members of the said channels, and means coacting between one of the said binder members and one set of said side flanges for normally pressing the 5 said binder members against the outer set of said flanges.

2. In a temporary binder and in combination with the covers and a connecting back therefor, a binder comprising plates secured 10 adjacent the ends of the back and each having a channel extending across the back and side flanges extending at right angles to the back, a plurality of binder strips each being slotted at its ends to engage the outer member forming the said channels of said plates, and means coacting between one of the said binder strips and one set of the said side flanges for normally pressing the said binder strips against the other set of side 15 flanges.

3. In a temporary binder and in combination with the covers and a connecting back

therefor, a binder comprising plates secured adjacent the ends of the back and each having a channel extending across the back and side flanges extending at right angles to the back, a plurality of binder strips each being slotted at its ends to engage the outer member forming the said channels of said plates, and springs attached to one of the 25 outer binding strips, each spring being adapted to yieldingly engage a side flange of one of the said plates to normally press the ends of the said binder strips together and against the other side flange of the corresponding plate. 30

In testimony whereof we affix our signatures in presence of two witnesses.

OSKAR SIMENSEN.
AXEL COLBAN.
